UNITED STATES PATENT OFFICE.

EDWARD C. RETHORN, OF BUFFALO, NEW YORK, ASSIGNOR TO HERMAN WILE & CO., A CORPORATION OF NEW YORK.

TROUSERS.

1,107,236.

Specification of Letters Patent.

Patented Aug. 11, 1914.

Application filed October 24, 1912. Serial No. 727,556.

To all whom it may concern:

Be it known that I, EDWARD C. RETHORN, a citizen of the United States of America, and a resident of the city of Buffalo, county 5 of Erie, and State of New York, have invented certain new and useful Improvements in Trousers, of which the following is a full, clear, and exact description.

The principal object of my invention has 10 been to provide trousers, the waistband of which may be adjusted in size so that it will at any time meet the requirements of either the dealer or the wearer and thereby obviate the necessity of alterations in the 15 garment and at the same time preserve the proper fit and neat appearance.

Another object has been to provide trousers which will be cut in such a manner 20 that they will fit neatly to the wearer without overlapping or wrinkling at the waist line, no matter what the adjustment of the waistband may be, and thus obviate the use 25 of suspenders and the side or back buckle straps.

Reference is to be had to the accompanying 30 drawings forming part of this specification, in which like characters of reference indicate like parts throughout the several views of which:

Figure 1 is a perspective view of the 35 upper portion of a pair of trousers and shows the embodiment of my invention. Fig. 2 is a side elevation of the same and shows one portion of the belt removed and one of 40 the side flaps folded back. Fig. 3 is a fragmental side view of the waist portion of my improved trousers and shows the manner of cutting the placket in the same.

In the drawings, 5 represents the waist 45 portion of the trousers and 6 the waistband thereof. The material forming the waist portion of the trousers is cut at each side along the lines 7, 8 and 9, as shown in Fig. 3, thus forming front and rear portions 11 50 and 10, respectively. When the trousers are being made up after the material has been cut in the manner just described, the portion 10 is brought over and overlapped on the portion 11 and sewed down on to the same along the line 8 and the line 7 between the point 12 and the lower end 12^a of the cut, as indicated in Fig. 2. From the point 12 55 to the waist line the front and rear portions 11 and 10 are left loose, thus forming front and rear flaps 13 and 14, respectively.

Secured to the rear edge of the front flap 13 and on its outer surface is a hook 15, which is engageable with one of a plurality of eyes 16 equally spaced and secured to the inner surface of the rear flap 14. An eye 17 is also secured to the outer edge of the inner surface of the flap 14 and is engageable with one of a plurality of eyes 18 equally spaced and secured to the outer surface of the front flap 13. 60

So as to add to the strength and neatness of my garment, I provide a half belt which comprises two parts 19 and 20. The inner end of each of the parts 19 and 20 is secured between the materials forming the 70 rear flaps 14 and preferably near the edges thereof. These belt parts are preferably passed through tunnels 21 provided at the front of the waistband of the trousers. The belt part 20 is provided with an adjustable 75 buckle 22, so that the buckle may always be kept at the center of the waistband no matter what the adjustment of the same may be.

It will be seen from the accompanying 80 drawings, that in order to adjust the waistband of my trousers, it is only necessary to unhook the hooks 15 and 17 from the eyes 16 and 18 and then move the rear flaps 14 to the position where the waistband will 85 neatly fit the wearer, whereupon the said hooks may then be secured to the eyes which are nearest the adjusted position. When so adjusted the belt parts 19 and 20 are drawn up or let out as required and the buckle 22 90 adjusted so as to be at the center of the waistband.

By making the cuts in the waist portion along the lines 7, 8 and 9, as previously described and then sewing the material so as 95 to make a seam along the cut edges represented by the line 8 and the lower part of the line 7, the material in the trousers is so arranged that when the waistband is adjusted to its largest or smallest size, the 100 trousers will always have a neat and finished appearance and wrinkling of the same is thus prevented.

Obviously, if desired, single fastening 105 means may be provided on each set of flaps instead of the double fastening means shown, as well as other modifications of the details herein shown and described, without departing from the spirit of my invention or the scope of the appended claim 110

and I do not wish to be limited to the exact embodiment herein shown and described.

Having thus described my invention, what I claim is:

- 5 A pair of trousers comprising, a waist portion, a front and rear flap at each side of the rear center of said waist portion, each pair of said flaps being formed from a single piece of material, a triangular piece of material being removed at a point below each pair of flaps and below the waist line and the two edges of the cut portion being secured together, the circumference of the trousers at the upper part of the triangular
- 10 cut being comparatively less than the circumference at the lower end of the triangular cut and comparatively less than the circumference of the material at the upper
- 15

edge of the trousers, suitable fastening means spaced apart and secured to each of said front and rear flaps, so that they may be lockingly engaged, belt parts, each having one of its ends secured to said rear flaps, and tunnels provided on the front of said waist band through which said belt parts 25 pass, whereby the circumference of the waist band may be adjustably altered as desired.

In testimony whereof, I have hereunto signed my name in the presence of two subscribing witnesses.

EDWARD C. RETHORN.
